UNITED STATES PATENT OFFICE.

BENEDICT T. GIBBS, JR., OF CHICAGO, ILLINOIS, ASSIGNOR TO MORDEN FROG & CROSSING WORKS, OF CHICAGO, ILLINOIS, A CORPORATION OF ILLINOIS.

REINFORCEMENT FOR FROGS AND CROSSINGS.

1,313,480.

Specification of Letters Patent.

Patented Aug. 19, 1919.

Application filed March 1, 1919. Serial No. 280,004.

To all whom it may concern:

Be it known that I, BENEDICT T. GIBBS, Jr., a citizen of the United States, residing at Chicago, in the county of Cook and State 5 of Illinois, have invented a certain new and useful Improvement in Reinforcements for Frogs and Crossings, of which the following is a specification.

It is often desirable and necessary to 10 reinforce frogs, crossings and other track structures which are made of cast metal in such a manner that should the casting crack or fracture, the broken parts will be securely held in place and kept in proper 15 alignment. Such reinforcement has hitherto been in the form of separate metal parts or straps which have been bolted onto the casting structure; and due to the vibration of the track the bolts and reinforcement 20 loosen and fail to perform their proper function.

The object of this invention is to so reinforce such cast metal frogs, crossings or other track structures, in the process of 25 manufacture that the reinforcement becomes an integral part of the casting and cannot under any circumstances become separated therefrom; thereby holding all 30 parts of the casting in proper place should breakage occur and thus preventing possible derailment of trains passing over the structure. A further object of the invention is to reinforce frogs, crossings or other track structures of cast metal with straps or 35 bars of non-readily breakable material, so shaped that they are securely held and bound in place by the surrounding cast metal. The invention further consists in the means for doing this economically and providing a device which is satisfactory in use 40 and is not readily liable to get out of order. More particularly, the invention consists in the features and details of construction which will be hereafter more fully set forth 45 in the specification and claims.

Referring to the drawings, in which similar numerals represent the same parts throughout the several views.

Figure 1 is a plan view, partially in 50 section, of a crossing embodying this invention in its preferred form.

Fig. 2 is a sectional view on the line 2—2 of Fig. 1.

Fig. 3 is a side view of that part of the 55 device illustrated in Fig. 2.

Similarly, Fig. 4 is a plan view of a frog embodying this invention in its preferred form.

Fig. 5 is a sectional view on the line 5—5 of Fig. 4, and

Fig. 6 is a side view taken at the right of Fig. 5.

As has heretofore been indicated, the invention applies generally to track structures. For the purposes of illustration, it is shown in the first three figures, (1-3) as applied to a crossing of cast metal 10 and in the remaining figures (4-6) as applied to a frog 11. Except for the difference in shape caused by the variations in form between the crossing 10 and the frog 11, both of which will be hereafter referred to generically as the hard metal member, the structures are the same and are so correspondingly lettered.

The hard metal member is cast around pairs of reinforcing strips 12 of non-readily breakable material so placed that in the finished product they lie embedded in opposite sides of the casting and are held firmly in place therein. One means adopted for holding the strips in place consists in inclining the upper and lower edges 14 of the bars 12 to the vertical faces of the hard metal member so that the bars are of greater height on their faces which are toward the center of the hard metal member than at the outer sides thereof, with the result that the metal of the hard metal member embraces each bar, as clearly appears in the drawings, to prevent lateral movement of the bar with reference to the cast member. Again, the bars are held against longitudinal movement with reference to the hard metal member through the use of lugs 15, of the cast metal, which enter suitably formed recesses 16 conveniently located along the top and bottom surfaces of the bars. These lugs 15 obviously tend to prevent longitudinal movement of the bars with reference to the hard metal member. Either one of these methods may be used singly.

The bars are further held in place by providing cast metal knobs 17 formed integral 105 with the hard metal member itself which flow into the holes 18 formed at convenient intervals along the reinforcing bars. The holes may be made tapered or cylindrical, as desired. The bulk of these knobs pre- 110

vents longitudinal movement of the bars. When made tapered, the taper prevents lateral movement of the bars with reference to the hard metal member.

5 The result of the complete construction shown and described is that the hard metal members are for all practical purposes cast integral with substantially non-breakable members, which reduce breakage in and prevent accidents due to breakage of the hard metal member.

Having thus described my invention, what I claim as new and desire to secure by Letters Patent, is:—

15 1. A railroad trackage structure of the frog, crossing or like type, comprising a cast member of the required shape, and a reinforcing strip secured to a side of the member to maintain assembly of constituent parts of said member upon breakage thereof.

20 2. A railroad trackage structure of the frog, crossing or like type, comprising a cast member of the required shape, and a reinforcing strip incorporated into interlocking relation with a side of the member to maintain assembly of constituent parts of said member upon breakage thereof.

25 3. A railroad trackage structure of the

frog, crossing or like type, comprising a cast member of the required shape having 30 a dove-tail groove in a side thereof, a reinforcing strip incorporated in said groove to maintain assembly of constituent parts of said member upon breakage thereof, and means for locking said reinforcing strip 35 against longitudinal movement relative to the member.

4. A railroad trackage structure of the frog, crossing or like type, comprising a cast member of the required shape having 40 a dove-tail groove in a side thereof, a reinforcing strip incorporated in said groove to maintain assembly of constituent parts of said member upon breakage thereof, and inwardly tapering lugs projecting from the 45 bottom of the groove and engaged in corresponding openings of the reinforcing strip.

In witness whereof, I have hereunto subscribed my name in the presence of two 50 witnesses.

BENEDICT T. GIBBS, JR.
